ATTORNEY

UNITED STATES PATENT OFFICE.

JOHN KIEFER, OF HAMILTON, OHIO.

HOE.

SPECIFICATION forming part of Letters Patent No. 230,552, dated July 27, 1880.

Application filed June 12, 1880. (No model.)

To all whom it may concern:

Be it known that I, JOHN KIEFER, of Hamilton, Butler county, Ohio, have invented certain new and useful Improvements in Hoes, of which the following is a specification.

5 My invention relates to hoes having the eye manufactured in a separate piece from the blade.

In the accompanying drawings, Figure 1 is 10 a front elevation of the blade and eye, with part of the latter in section, and Fig. 2 is a vertical section of eye and blade.

The blade A is cut from a flat plate. At the 15 front of the blade is a mortise, D. The eye or ferrule B has a curtain-like flange, F, at its front end, and from the inside of this flange the tenon E projects inwardly.

The blade fits up under the flange F, as 20 shown, and the mortise D is hooked over the tenon E. If desired, the mortise may be in the flange and the tenon may be formed on the blade.

25 At the bottom of the ferrule, at the front end, is formed a hook-stud, I, and the blade of the hoe has a hole in it, adapted to admit this stud after the blade is hooked at the top, as before mentioned. The stud I is a hook, by reason of the notch M in its under side.

If the stud be bent downward slightly after 30 the parts are in proper position the notch will lock over the edge, the blade in the stud-hole, and the parts will be locked together, and the device may, in a way, be said to be complete.

In practice I prefer to provide the ferrule 35 with a lip, L, at the back of the blade, in order that the rivet K may be inserted through both lip and blade. While these fastenings act best in combination, I find that they are somewhat effective when used separately—that is, 40 the stud I may be used to the exclusion of the rivet K, and vice versa.

A bolt, G, passes across the ferrule, as shown, and is adapted to retain a handle placed in the ferrule. If this bolt be tightened the ferrule will be somewhat flattened, and if the 45 hook-stud I has not been bent downward to hook over the blade the squeezing of the ferrule will tend to force the hook downward till it locks firmly on the blade, in an obvious 50 manner. The bending of the hook-stud is thus seen to be really non-essential.

After the hook is forced down to lock the blade, or before it is done, the wedge H may be driven in above it, between it and the upper edge of the stud-opening, and into the 55 handle of the hoe. The lip J upon the stud I may be bent up, as shown, to retain the wedge.

This form of lock is peculiarly solid and substantial, and cannot give way so long as the handle is in the ferrule.

60 In practice I find that simply driving the handle into the ferrule tends to force the hook down tightly and solidly.

Longitudinal ribs C are cast in the ferrule, to prevent the turning of the handle, and to 65 cause more of an up-and-down stretching strain on the ferrule as the handle is driven in. This aids the locking at the hook. Two ribs, one at the bottom and one at the top, as shown, may be used, or one may act alone.

70 The ferrule should be of a somewhat malleable material, unless the rivet K is depended on entirely for the lower lock.

I claim as my invention—

1. The ferrule B, having curtain-flange F 75 and lip L, combined with the blade A, adapted to engage inside the curtain-flange by mortise and tenon, and to be riveted to the lip L, substantially as set forth.

2. The ferrule B, having curtain-flange F, 80 adapted to engage outside the blade by mortise and tenon, and the hook-stud I, adapted to engage with the blade by passing through an opening and hooking downward, arranged substantially as set forth.

85 3. The ferrule B, blade A, curtain-flange F, inside mortise and tenon top-lock, D E, hook-stud I, and compression-bolt G, combined substantially as set forth.

4. The ferrule B, blade A, inside mortise 90 and tenon, D E, hook-stud I, and wedge H, combined substantially as set forth.

5. The ferrule B, rib C, one or two, curtain-flange F, blade A, inside mortise and tenon, D E, and hook-stud I, combined substantially 95 as set forth.

JOHN KIEFER.
